UNITED STATES PATENT OFFICE.

ALBERT P. McGRAW, OF McGRAW, NEW YORK.

CORSET.

SPECIFICATION forming part of Letters Patent No. 741,697, dated October 20, 1903.

Application filed February 27, 1903. Serial No. 145,383. (No model.)

To all whom it may concern:

Be it known that I, ALBERT P. McGRAW, of McGraw, New York, have invented a new and useful Improvement in Corsets, which invention is fully set forth in the following specification.

My invention relates to corsets, and more particularly to the manner of inclosing the corset-steels in their pockets, seaming the corset-body to said pockets, and covering said seams, so as to protect the same and strengthen the corset at this point where great strain and wear occur.

Heretofore it has been customary to stitch the steel in a pocket and stitch the pocket to the body.

The object of the present invention is to inclose the steel in its pocket, unite it to the body, and provide a protecting-cover and finish to the joint, all in such manner as to afford a union of great strength and durability at this critical point in the corset's construction.

With this object in view the invention consists in a corset-steel inclosed in a suitable pocket, a corset-body arranged so as to form a joint with said pocket, and a finishing and protecting cover over said joint, all united by a suitable seam or line of stitches. With such a construction I am able to construct a corset of great strength at this vital point efficiently protected and smoothly finished, the whole being completed at one operation, thereby securing a superior construction with a minimum expenditure of labor.

The invention is illustrated in the accompanying drawings, in which—

Figure 1 is a front elevation showing a corset-steel, its pocket, and the manner of uniting the same to the corset-body and covering and finishing the joint; and Fig. 2 is a cross-section on line *x x*, Fig. 1.

In said drawings, 1 is a corset-steel of usual or any suitable construction inclosed in a pocket 2, which pocket has one of its edges 3 folded over the other edge 4, as shown. The edge 5 of the body material 6 is then laid above the overlapped edges 3 and 4 of the pocket 2 and the covering-strip 7 placed over the whole, and a line of stitching 8 unites the overlapped edges of the pocket, the body 6, and the covering-strip 7. A second line of stitching 9 unites the cover-strip 7 to the pocket 2 and may also, if desired, engage the edge 5 of the body 6.

Having thus described my invention, I claim—

In a corset, a strip of material folded to form a steel-pocket and having one of its rear edges folded over the other, a corset-body with its edge superimposed on the folded edges of the pocket, a cover-strip lying over the edges of the body and pocket, and a line of stitches passing through all the parts.

In testimony whereof I have signed this specification in the presence of two subscribing witnesses.

ALBERT P. McGRAW.
